CLAIM

The ornamental design for a TV remote control for the manually handicapped, as shown and described.

DESCRIPTION

FIG. 1 is a top front perspective view of a TV remote control for the manually handicapped showing my new design with indicia on the control buttons omitted for convenience but shown in FIG. 2;

FIG. 2 is a front elevation view thereof including the preferred indicia on the control buttons;

FIG. 3 is a top plan view thereof; the bottom plan view is the mirror image of the top;

FIG. 4 is a left side elevation view thereof; the right side elevation is the mirror image of the left side; and,

FIG. 5 is a rear elevation view.

FIG.1
